UNITED STATES PATENT OFFICE.

HENRY HARRILD AND GUILFORD ROWE HARRILD, OF SPOKANE, WASHINGTON.

KITCHEN-CABINET.

No. 893,492.

Specification of Letters Patent.

Patented July 14, 1908.

Application filed April 29, 1907. Serial No. 370,827.

To all whom it may concern:

Be it known that we, HENRY HARRILD and GUILFORD ROWE HARRILD, citizens of the United States, and residents of Spokane, 5 in the county of Spokane and State of Washington, have invented certain new and useful Improvements in Kitchen-Cabinets, of which the following is a specification.

This invention is an improvement in 0 kitchen cabinets, and consists in certain novel constructions and combinations of parts as will be hereinafter described and claimed.

In the drawing Figure 1 is a perspective view of the cabinet with the top lowered. 5 Fig. 2 is a perspective view with the top raised. Fig. 3 is a top plan view, the top being removed and the parts in the position they assume when the top is lowered. Fig. 4 is a vertical section, parts being broken 20 away illustrating some of the operative parts in the position they assume when the top is lowered. Fig. 5 is a sectional view similar to Fig. 4, and showing the parts in the position they assume when the top is 25 raised. Fig. 6 is a detail view of one of the supporting arms for the work-board. Fig. 7 is a detail view of the work-board, and Fig. 8 is a detail view of one of the connecting rockers.

30 In carrying out the invention we provide a table frame having the opposite side frames A supported on the legs B and C and having outer and inner slide rods p and q which are slotted at c, for the passage of bolts r and s to 35 limit the movement of said slide rods, the said slide rods being adapted to be extended beyond the table frame as shown in Fig. 3. The top D is hinged at its rear edge to the 40 table frame so it may be raised and lowered and is provided on its under side with a drawer frame D' which may be supplied with a number of drawers for holding any desired articles and this drawer frame D' is preferably pivoted at D² so it will swing on its 45 connection with the top between the positions shown in Figs. 1 and 2 when the top is lowered or raised as illustrated in said figures.

A work-board l is arranged below the top D and this work-board is preferably movable 50 vertically up and down and devices are provided whereby it may be so moved in order that it may be raised to the desired level for use when the top is raised and then lowered out of the way when the top is lowered to 55 make room for the said top or the parts on the under side thereof, as before described.

We also provide a supporting board i hinged at its lower edge at j and arranged for adjustment to the position shown in Fig. 2 in order to support the front edge of the work-board and to give the same additional strength at such point, and this hinged board i may be raised from the position shown in Fig. 4 to that shown in Fig. 5 by hand openings k being provided therein for introduction of the fingers of the operator in raising the board i, as before described.

The work-board l is provided at its rear end with boxes or tills u for spices and the like and at its opposite ends at its rear edge 70 it is provided with laterally projecting bolts or studs o which enter upright grooves m in the table frame, see Figs. 3, 4 and 5, and prevent any forward movement of the work-board l in the use thereof and stops n, are arranged at the upper ends of the grooves m to limit the upward movement of the work-board, by the devices operating below it as presently described, or the groove m may be extended to the upper end of the frame bars 80 as shown in Fig. 3.

Supporting arms a and b are pivoted at one end to the table frame and are provided at their other or swinging ends with rollers a' and b' which bear below the work-board l 85 and the swinging ends of the arms a and b are connected by links d so the said arms a and b will rise and fall in unison and means are provided for adjusting the arms from the position shown in Fig. 4 to that shown in Fig. 5 90 and vice versa. The arms a and b are arranged in pairs at the opposite sides of the table as shown in Fig. 3, and the arms a are secured at their pivoted ends on shafts e' at one end of the rocking arms e, the said shafts 95 e' being journaled in the table frame and the arms e swinging between stops h and h' which permit their movements in both directions and the swinging ends of the supporting arms e are connected with the top D by means of 100 links f which are preferably slotted at f' to receive the bent ends e² of the arm e, as shown in the drawings.

In the operation of the described construction when the top D is lowered as shown in 105 Fig. 1, the parts are in the position shown in Figs. 3 and 4, the supporting arms being lowered and the work-board being dropped to the position best shown in Fig. 4, and being at such time out of the way of the parts 110 on the under side of the top D. If now, the top be raised from the position shown in Fig.

1 to that shown in Fig. 2, the supporting arms will be rocked to the position shown in Fig. 5 gradually lifting the work-board to the position shown in said Fig. 5, thus raising it 5 to the desired height and the supporting board *i* may then be lifted from the position shown in Fig. 4 to that shown in Figs. 2 and 10 5 in which it will form a firm support for the front end of the work-board, as will be understood from the drawings.

In connecting the links *f* with the top board it may be preferred to employ perforated plates *g* on the top and to hook the upper ends of the links *f* at *f*² for engagement 15 with the said plates, as will be understood from Figs. 1 and 2 of the drawings.

We claim—

1. A cabinet substantially as herein described comprising a frame provided with 20 vertical grooves, a work-board movable up and down in the frame and having lateral projections entering the upright grooves, supporting arms arranged in pairs below the work-board and pivoted at one end to the frame and provided at their other or swinging ends with rollers bearing below the work board, means connecting the swinging ends 25 of the supporting arms, swinging arms piv-

oted at one end to the frame and connected at such end with one of the supporting arms 30 for operating the same, a hinged top, connections between the said top and the swinging arms whereby the arms may be operated by the raising and lowering of the top and a supporting board hinged at one edge to the 35 frame whereby it may be adjusted at its other edge to bear below the work-board when the latter is raised to position for use and form a support for said work-board, substantially as set forth.

2. The combination with a frame and a top, of a work-board movable up and down in the frame below the top, means for raising the work-board, and a supporting board pivoted at its lower edge, free at its other edge 40 and adjustable at the latter edge to a position below the front edge of the work-board when the latter is elevated to support the same when raised to position for use, substantially as set forth.

HENRY HARRILD.

GUILFORD ROWE HARRILD.
